METHOD OF AND APPARATUS FOR STRAIGHTENING VIOLIN BOWS

William H. Gentile, Sacramento, Calif.

Application June 24, 1957, Serial No. 667,642

1 Claim. (Cl. 144—261)

The invention relates generally to devices and processes for straightening the bows of stringed instruments and, more particularly, to an apparatus for and method of correcting the curvature of bows which, for any reason, have acquired a misalignment over any portion or all of their length.

While the device and process is applicable to bows used in conjunction with any of the stringed instruments, violin bows, owing to their greater numbers and conditions of use, are the kinds of bows most often found as requiring realignment.

Every bow, as it originally leaves the factory, has formed therein a curvature of predetermined arc so as to exert a tension on the hair. When viewed from above the un tensioned bow is linear; when viewed from the side, however, the un tensioned bow is seen to have a sweep, the hair largely causing the sweep to disappear as tension is applied to the hair.

Undue exposure to the elements or accidental application of weight for any length of time to a portion of the bow frequently produces a "set" or bend in or improper curvature to the bow. Furthermore, prolonged hair tension often results in a straightening of the bow. In either event, it is necessary in order to effect repair to realign or reestablish in the bow the proper curvature.

It is therefore an object of the invention to provide an inexpensive and quick yet accurate method of and apparatus for re-setting bows to proper curvature.

It is another object of the invention to provide a generally improved process of a device for straightening bows used in connection with any of the stringed instruments.

It is yet another object to provide a method of and apparatus for establishing the correct curvature in any bow device, such as a cross-bow or long-bows used to propel arrows, for example.

Other objects, together with the foregoing, are attained in the method described hereinafter and in the embodiment described in the following description and shown in the accompanying drawings in which:

Figure 1 is an elevation of the straightener from the right side;

Figure 2 is a bottom plan;

Figure 3 is a longitudinal section, to an enlarged scale, of the torsion collar, the plane of section being indicated by the line 3—3 in Figure 1;

Figure 4 is a median longitudinal section, to an enlarged scale, of the torsion collar, the plane of section being indicated by the line 4—4 in Figure 2;

Figure 5 is a top plan showing, alongside the straightener, a typical bow having an off-set curve to the right over a portion of its length;

Figure 6 is a view comparable to Figure 5 but with the torsion collar and the bow both inclined to the left at a predetermined angle; and

Figure 7 is a bottom view, to an enlarged scale, of the torsion collar end of the straightener, showing the bow in the straightener preparatory to heating.

2

While the method is capable of being practiced in several variant forms and the apparatus is susceptible of numerous physical embodiments, the process and device herein shown and described have been used numerous times with eminently successful results.

The straightener, generally characterized by the numeral 12, includes an elongated tube 13 of a material having a substantial thermal conductivity, brass being very satisfactory.

10 The tube length and inner diameter will vary, depending on the types of bows to be handled. In its preferred form, the length of the tube approximates the length of the bow to be treated, whereas the inner diameter of the tube is somewhat in excess, for example 15 25% to 50% greater, than the maximum transverse dimension of the bow.

To produce the desired results, the tube must be bent to an arcuate configuration having a predetermined radius of curvature whose value is quite critical. This 20 radius is such that with an over-all straightener length of twenty-six inches, the distance 14 (Figure 1) between a chord 16 drawn between the ends of the straightener curvature and the point 17 of maximum altitude is two and one-half inches.

25 To enable the user to determine accurately the location and extent of the misalignment on the bow a plurality of scribe marks 21 are etched on the tubing at regular intervals. Each of the scribe marks is further identified by one of a plurality of indicia 22, such as for example, the first number being "1," the second "2," etc., as appears most clearly in Figures 5 and 6, the numbers commencing at the upper or tip end 23 of the tube and progressing toward the lower or handle end 24 of the tube. Conveniently, the indicia 22 are scribed only on the upper or inside curved surface 26 of the tube. The scribe marks 21, on the other hand, completely encircle the tube and therefore the scribe marks are also visible on the lower or outer side 27 of the curved tube surface, that is to say, on the surface of the tube most distant 30 from the center of curvature.

In order to hold the bow at the required degree of angularity, a torsion collar 31 is provided. The torsion collar 31 comprises a sleeve portion 32 encompassing in rotatable relation a subjacent extension 33 of the tube 45 13. As shown most clearly in Figures 3 and 4, the collar 31 is prevented from upward translation by a bell-mouthed or flared portion 34 of the tube extension 33; downward translation of the collar 31 on the other hand, is blocked by an interfering shoulder 36 of a ring 37 secured to the tube 13 as by brazing 38.

The tip 41 of the bow, as appears most clearly in Figure 7, is snugly confined between a pair of scrolls 42 converging in a downward direction to define a triangular shaped chamber 43 accommodating the bow tip 41 in 55 fully lodged position of the bow. The inclined walls of the scrolls 42 serve to guide the bow tip into proper position and to hold securely the tip to the selected angular displacement. The scrolls 42 are themselves formed by slitting longitudinally the somewhat flared extension 46, or bell-mouth, of the collar 31, the material adjacent the slit being rolled or curled back as shown. The extreme upper end of the bell-mouth 46 is provided with a bevel 47, the bevel 47 serving, in conjunction with the converging walls of the bell-mouth and the scrolls, 60 smoothly to direct the bow tip into fully lodged location as the bow is inserted in the collar and the tube.

A clamping mechanism, generally designated 51 (Figure 1), enables the user to lock the collar 31 to the tube at any desired degree of relative angular displacement. A longitudinal slot 52 in the collar for approximately the lower two-thirds of the collar length is provided. A thumb-screw 53 passes through an unthreaded aperture

in a near ear 54, thence through and in threaded engagement with the threaded opening in a far ear 56 spaced from the near ear 54, the ears being mounted on the collar 31 and straddling the slot 52. A shoulder 57 on the thumb screw 53 bears against the near ear 54 as the screw is taken up and urges the ear 54 toward the ear 56, the slot 52 being narrowed accordingly, a powerful clamping effect being the result.

Appropriate indicia 61 on the ring 37, which is secured to the tube 13, indicate angular displacement of the collar with respect to the tube, the collar slot 52 serving as an index. Diametrically opposite the slot on the opposite wall of the collar is an auxiliary collar index 62, as appears in Figures 2 and 7 whereas an auxiliary ring index 63 appears on the ring directly opposite the center or base mark 64 (Figure 6) of the angular displacement indicia 61. Obviously, as the slot 52 is displaced in a given direction and amount from the ring's center mark 64, the auxiliary collar mark 62 is displaced an identical amount, and in the same angular direction, from the auxiliary ring mark 63, all as is shown most clearly in Figures 6 and 7. This enables the user to know that displacement exists, if it does, regardless of the position from which the straightener is viewed.

The manner of operation of the device appears in Figures 5-7. The user, having previously removed the "frog" (not shown) from threaded engagement with the handle or butt end 71 of the bow 72, places the "frog" and its attached hair 73 slightly to one side, the other end of the hair 73 still remaining attached to the bow tip 41 in the customary fashion. Straightening can be effected, in other words, without detaching the hair from the tip.

It will be assumed, for purposes of explanation, that through some mishap, the bow 72 is defective in that it has a bend or curve 76 in it for a portion of its length, the bend extending approximately between the upper location 77 and the lower location 78; furthermore the bend constitutes an arcuate displacement to the right, as shown in Figure 5.

The user thereupon grasps the butt end 24 of the straightener and the butt end 71 of the bow and places the two devices substantially in side by side relation, as appears in Figure 5. It will be noted that as the user looks downwardly on the straightener and the bow when they are in proper position the numerals 22 on the straightener face the user and are in correct attitude. Additionally, the cavity 43 between the scrolls 42 points away from the user, thus indicating to him that the bow tip 41 is likewise to be positioned, so that the shoe 79 of the tip faces away from the user.

The user, having properly oriented the straightener and the bow then takes mental note of the fact that the curve extends between the etched numerals "1" and "4" on the straightener and that maximum deflection occurs approximately at a location one fourth of the way from "2" toward "3".

The bow is thereupon inclined about its own axis so that the curved or bent portion of the bow is swung upwardly and tends to disappear or merge into alignment with the rest of the bow, as shown in Figure 6. This operation involves, with a right-hand bend, as shown, an inclination or tipping of the bow to the left, about its own axis, approximately thirty degrees or so, as appears in Figure 6. Then, still holding the bow in canted attitude, the user rotates the collar 31 a corresponding amount and in the same angular direction, judging by eye. When this has been done, the collar is tightly clamped and the bow is inserted butt end first in the tube and is pushed "home" in such a fashion that as the bow is fully lodged the bow tip 41 is confined between the scrolls, as appears most clearly in Figure 7.

At this juncture the bow is rather securely lodged within the tube and has been so oriented by the displaced collar position that the bent portion of the bow extending between the points 77 and 78 is opposed by the curvature of the walls of the straightening tube.

Thereupon, the user grasps the ends of the straightener and, holding the tube over an open flame, such as a Bunsen burner, moves the tube back and forth so that the flame plays over the tube between the mentally noted marks "1" and "4" etched on the tube, with major play occurring in the portion between "2" and "3" where maximum bow deflection was previously observed.

Heating proceeds until the heated portion is no longer bearable to grasping of the fingers around the tube at the heated portion. The tube and confined bow are, at this juncture, put aside and allowed to cool to ambient temperature. The bow is thereupon removed and will have assumed in every respect its original or correct configuration.

Where the problem is not to correct a curve or bend but to return the bow to its original proper tension producing curvature, the bow having been overly straightened by prolonged hair tension, or other reason, the following procedure is followed. With the collar locked in middle or central location, as shown in Figure 5, the bow is inserted in the straightener and pushed home so that the tip 41 is lodged between the scrolls. The entire tube, rather than just a portion thereof, is heated over the burner until the tube surface is too hot to grasp. The straightener is thereupon allowed to cool to room temperature. After cooling, the bow is removed from the straightener. The bow, as it is taken out, is found to have set in it the proper bow configuration and is ready to have the frog re-placed and the hair tensioned. It has been found as a final step that vigorous polishing, in a reciprocating longitudinal direction, with any of the better standard bow polishes serves not only to give the bow an attractive appearance but also to "set" the bow fibers.

It can therefore be seen that I have provided a method of and apparatus for properly configuring a wooden, or comparable, bow, and for accomplishing this result in quick and inexpensive fashion.

I claim:

A bow straightener comprising a tube of heat conducting material, said tube being curved to assume a predetermined radius of curvature and having a tip end and a handle end, said tube also having an upper side and a lower side, said lower side being more distant from the center of curvature than said upper side, said tube being etched by a plurality of equally spaced scribe marks disposed along the length of said tube, said tube also being etched by a plurality of progressively higher valued indicia each adjacent one of said scribe marks, a torsion collar encircling and rotatably mounted on said tip end of said tube and extending beyond the end of said tube, said torsion collar including a pair of spaced oppositely curled scrolls defining a pair of converging walls adapted to receive and confine the tip of a bow, said collar also including means for clamping said collar to said tube at predetermined values of angular displacement, and means for ascertaining said values of angular displacement.
